UNITED STATES PATENT OFFICE.

CLARA OLIVE BILINSKI, OF DIAMOND LAKE, ILLINOIS.

CLOTHES-SPRINKLER.

SPECIFICATION forming part of Letters Patent No. 310,020, dated December 30, 1884.

Application filed June 6, 1884. (No model.)

To all whom it may concern:

Be it known that I, CLARA OLIVE BILINSKI, of Diamond Lake, in the county of Lake and State of Illinois, have invented a new and Improved Clothes-Sprinkler, of which the following is a full, clear, and exact description.

The object of my invention is to provide a simple, effective, and inexpensive device for sprinkling clothes for laundry and household purposes; and it consists in the construction and combination of parts, as will be herein-after fully described and claimed.

Reference is to be had to the accompanying drawings, forming part of this specification, in which similar letters of reference indicate corresponding parts in both the figures.

Figure 1 is a front elevation, partly in section, of my improved clothes-sprinkler. Fig. 2 is a vertical transverse section.
20 The standard A is provided with a shelf, B, at its lower end, to which are attached screw-clamps C, for securing the said standard to the table. The upper end of the standard A is provided with a shelf, D, for supporting the pail E, and is furnished with a standard, F, for receiving the bail of the said pail and retaining it upon the shelf D. A flexible rubber tube, G, connected with the pail E, leads to the sprinkler-nozzle H through a pinch - cock, I, resting upon the shelf B. The pinch-cock I consists of a block, J, bored longitudinally to receive the tube G, and provided with a lever-spring, a, which carries at its free end a loop, b, extending downward through holes in the block beneath the tube, and adapted to be drawn upward by the lever-spring a, so as to close the tube G. A wire loop, c, extending upward through the shelf B and block J, passes over the top of the lever-spring a, and is connected at its lower end with a pedal, K. The inclination of the nozzle H may be varied by means of a button, L, secured to the side of the standard A and pressing upon the top of the rubber tube G. A cup, M, attached to the standard A below the sprinkler-nozzle H, receives the water that may drip from the said nozzle. The pail E is placed at a sufficient height above the nozzle H to insure the discharge of the water through the said nozzle in the form of

a fine spray. Where the house is furnished with water from the street-supply, the tube G may be connected with the water-pipes and the pail E may be dispensed with. Clothes to be sprinkled are placed upon the table 55 within range of the nozzle H, and the pedal K is pressed by the foot, the lever-spring a is drawn downward, and the tube G is relieved of the pressure of the loop b. The water is then discharged in a fine spray from the nozzle H upon the clothes. When the pedal K is released, the spring I raises the loop b and presses the tube G, thereby stopping the flow of water.

I am aware that a nasal douche has been 65 constructed of a reservoir, flexible tube, and a nose-piece; also, that a washstand has been provided with a flexible outlet-pipe and with a spring pinch-cock constructed to close the pipe, and adapted to be withdrawn by a cord, 70 bell-crank lever, and a handle or lever; also, that a sprinkler for clothes has been constructed of a tube provided with a rose and stop-cock, and connected to a water-supply; and I do not desire to claim any such construction as of my invention. 75

Having thus described my invention, what I claim as new, and desire to secure by Letters Patent, is—

1. The combination of the longitudinally-apertured block J and the rubber tubing G, passed through the longitudinal aperture, with the lever-spring a, loop b, passing from the lever-spring a under the tube G, loop c, connected with lever-spring a, and the pedal 80 K, connected to the lower end of loop c, substantially as set forth.

2. The standard A, shelf B, and clamp C, in combination with the block J on said shelf, tube G, passing through said block, and 85 pinch-cock I, secured to the block for closing tube, substantially as set forth.

3. The combination, in a clothes-sprinkler, of the standard A, upper and lower shelves, D B, with the pail E, tube G, connected to 90 the pail, block J, mounted on the lower shelf, and pinch-cock I on the block J for closing the tube, substantially as set forth.

4. The combination, in a clothes-sprinkler, of the standard A, pail-shelf D, projecting at 95

right angles thereto, and the vertical extension F, for supporting the bail of a pail, substantially as set forth.

5. In a clothes-sprinkler, the standard A, provided with a slot, and the pivoted button L at one side of the slot, in combination with the sprinkling tube and nozzle G H, substan-

tially as set forth, whereby the tube may be held in place and the angle of the nozzle varied.

CLARA OLIVE BILINSKI.
